UNITED STATES PATENT OFFICE.

EDWARD G. BLOSER, JR., OF PHILADELPHIA, PENNSYLVANIA.

RUBBER HEEL.

Application filed March 4, 1926. Serial No. 92,225.

This invention relates to improvements in rubber heels and the like for footwear.

An object of this invention is to provide an improved rubber heel having a relatively 5 hard or metallic insertion therein, which will tend to cause the heel to wear evenly. The improved rubber heel with the insertion is so designed that the heel will not wear quicker on one side than on another, 10 and is especially advantageous where the rubber heel is so formed as by having a suction cup or the like formed upon its tread surface, reducing the size of the tread surface adjacent the rear of the heel.

15 With the foregoing and other objects in view which will be made manifest in the following detailed description and specifically pointed out in the appended claim, reference is had to the accompanying drawings 20 for an illustrative embodiment of the invention, wherein:

Figure 1 is a top plan view of the improved heel,

Fig. 2 is a vertical section taken on the 25 line 2—2 of Fig. 1, and

Fig. 3 is a bottom plan view of the heel showing the tread surface.

Referring to the accompanying drawings wherein similar reference characters designate 30 similar parts throughout, the improved heel consists of a heel-shaped body 10 formed of rubber or of similar composition. On the under side of the heel there is formed a concavity 11 forming a suction cup or the like. The concavity or suction cup 11 is used for illustrative purposes only, and it will be readily appreciated that in some instances this cup can be omitted entirely. Where the suction cup is employed, the 35 tread surface of the heel, indicated at 12, is materially reduced and the heel unless otherwise protected is very apt to wear on one side faster than on another. As a means for protecting against this disadvantage, a metallic insertion 13 is imbedded in the heel. This metallic insertion is preferably formed 40 of corrugated sheet metal of general U-shaped form and is arranged approximately parallel to the rear sides of the heel. Its bottom edge is substantially flush with the 45 tread surface 12, as clearly shown in Fig. 2, while the top of the insertion is disposed below the top surface of the heel. By this construction the metallic insertion being of relatively 50 hard material tends to keep the heel even during wear.

It will be noted that there is a small portion of rubber between the top of the insertion 13 and the top surface of the heel, and this affords a limited resiliency or spring for 60 the insertion when the weight is placed upon the heel. The purpose of using corrugated metal is for the reason that corrugated metal cannot easily loosen and drop out of the heel, especially in view of the fact that it 65 is molded in the body of the heel. Furthermore, it presents an edge which is distributed over a considerable area, making the insertion very effective.

By the improved construction it will be 70 readily appreciated that the improved heel is very advantageous in that it protects and strengthens rubber heels having limited tread surfaces, preventing the heels from wearing quicker in some portions than in others and tending to keep the heel wearing evenly.

It will be understood that various 75 changes in the detail of construction may be made without departing from the spirit 80 or scope of the invention as defined by the appended claim.

I claim:

A rubber heel having a cup-shaped depression formed in its bottom surface centrally of the heel, defining a semi-circular wall adjacent the rear of the heel and a flat portion adjacent the front of the heel, a sheet metal insertion embedded in, and molded in the heel to prevent said semi-circular wall portion from wearing, and to reinforce the same to prevent caving in thereof, said insertion extending generally about the back of the heel centrally between the back edge of the heel and the cup-shaped 90 depression, and having its width extend upwardly from the bottom of said wall, said insertion being corrugated to offer the maximum wearing surface to the ground, the bottom surface of the heel being flush with the bottom edge of the insertion and said insertion extending into the wall a distance considerably less than the thickness of said heel, whereby the presence of said insertion in said heel will detract little from the 95 resiliency of said heel.

In testimony whereof I have signed my name to this specification.

EDWARD G. BLOSER, JR.
